CALCULATING DEVICE

Walden Williams, Los Angeles, Calif.

Application September 4, 1951, Serial No. 245,053

9 Claims. (Cl. 35—31)

1

This invention has to do with calculating devices, and relates more particularly to a calculating device for use in teaching children such elementary mathematics as addition and subtraction, although it will be obvious that the device is capable of other uses.

It is an object of the invention to provide a simple and inexpensive device of this character which is capable of being used by children not only as an entertaining toy but also as a means of learning elementary mathematics.

A further and still more specific object is to provide in a device of this character simple and novel means by virtue of which, by moving a pointer to a given numeral, the answer to various other visually indicated problems will be denoted.

A still further object is to provide, in a device of this character an operating means which may be accomplished by an extremely economical and simple construction.

An additional object is to provide, in conjunction with the operating means, simple and effective means for preventing the movable tape element from shifting laterally in relation to its guide.

Other objects will appear hereinafter.

Without intending thereby to limit the broader scope of the invention, except as may appear from the appended claims, I shall now describe the invention in its presently preferred embodiment, for which purpose I shall refer to the accompanying drawings wherein:

Fig. 1 is a top plan view;

Figs. 2, 3 and 4 are enlarged sections taken upon lines 2—2, 3—3, and 4—4, respectively, of Fig. 1;

Fig. 5 is a perspective view of a modified form of pointer; and

Fig. 6 is a sectional view showing a modified form of guide.

Referring now to the drawings, I show at 5 a box-like rectangular housing, which may be made of wood, metal, chipboard or a suitable plastic, having end walls 6, 7, side walls 8, 9 and a bottom wall composed of sections 10 and 10a.

Bottom wall section 10 is made relatively thick, and the bottom wall sections are spaced apart to provide, through the bottom of the housing, a longitudinal medial slot 12.

The top surface of the bottom wall section 10 carries a longitudinal row of indicia 15 denoting, for instance, the numerals 1 to 20 inclusive. In applying said numerals it is my preference first to print them upon a tape 14 and then secure the

2

tape to the top surface of bottom wall section 10 as by cementing the tape to the surface.

A rectangular guide member 20 is secured at its outer side surface to the side wall 9 as by a suitable cement, or in any other suitable manner, the guide being spaced above the bottom wall section 10a. The inner side wall surface of the guide, together with the thickened portion of bottom wall section 10, defines the upper portion 10 of the slot 12.

A continuous flexible tape 30 extends around and is mounted to slide upon the guide 20. Indicia 40 is carried on the top surface of the tape, said indicia consisting of a row 41 of longitudinally spaced numerals 1 to 20 inclusive, which numerals progressively increase in value towards the left from a zero point z, and each of said numerals has before it a plus sign, i. e. "+" denoted by the numeral 41a. Also in linear relation to the indicia 41, I provide indicia 45 comprising a row of numerals 1 to 20 inclusive, progressively increasing in value to the right from the zero point. Before each of the latter numerals I display a minus sign, i. e. "—" denoted by the numeral 46.

A flat pointer 50 is secured to the top run of the tape at the zero point as by staple 51, although any other suitable means may be used for fixing the pointer to the tape. The top surface of the pointer may carry the indicia "ANS" denoted by the numeral 52, thus indicating the answer. A longitudinal channel 53 is provided in the top surface of the guide 20 to receive the staple 51 used for attaching the pointer to the tape.

The free end of the pointer presents bifurcations 54 which are sufficiently spaced apart to straddle the respective answer indicia 15, the bifurcations overlying the top surface of bottom wall section 10.

For moving the tape longitudinally of the guide I provide an operating member 60 in the form of a flexible loop of a material such as string, fabric or plastic, the loop passing over the pointer and being tied into a knot 61 at its free ends after being passed downwardly through the slot 12, so that the loop projects below the slot where it may be accessible for convenient manual operation, the knot being larger than the width of the slot so as to prevent the loop from being accidentally moved into the housing.

To provide a cover for the housing, I provide a longitudinal inwardly opening groove 65 in each side wall of the housing above the top surface of the bottom wall section 10, and above the tape 30, and mount a resilient transparent sheet 66 by

bowing the sheet and inserting its opposite side edges in the slots. The resiliency of the sheet maintains its edges in the slot. It is my preference to use a suitable plastic for the sheet 66.

From the foregoing description it will be apparent that, for subtraction problems, the row of numerals 45 is employed in conjunction with the numerals 15. The numerals 41 are arranged in progression to the left of the pointer for addition problems. In operation, if the pointer is moved to register with the numeral 8 in the row 15, as shown, which denotes the answer, by reference to the remaining numerals on the tape in relation to the numerals 15, it will be seen that the answer "8" is the correct answer to the various addition and subtraction problems presented by registration of the numerals on the tape with the numerals 15. For instance, 9-1=8, 10-2=8, 7+1=8, 6+2=8, etc.

It is apparent that various other calculations are possible from the arrangement described; and it is also apparent that instead of running the numerals in each row from 1 to 20, additional numerals and fractions may be added.

In operation there is sometimes a tendency of the tape 38 to move laterally over its guide towards the top surface of bottom wall section 10. I find that I am able effectively to prevent this by the simple modification of the pointer shown in Fig. 5, wherein the parts are as before described except that here the pointer 50a is provided with an outwardly opening recess 70 in each of its opposite side edge portions to receive the loop 60 and therefore to prevent longitudinal movement of the pointer within the loop. Inasmuch as the loop depends through the slot, any tendency of the tape to move laterally will cause the loop to engage the opposite side wall of the slot 12 and arrest the movement.

In Fig. 6 I show, in cross-section, a modified form of guide 29a wherein a longitudinal tape passing channel 80 is provided in the bottom surface of the guide.

It will be understood of course that I may make various modifications in the particular construction and arrangement of the parts described without departing from the broader scope of my invention.

I claim:

1. In a calculating device, a housing, stationary means in the housing presenting a longitudinal row of equidistantly spaced numerals progressively increasing in value from one end of said means to the other, movable means mounted in the housing for sliding movement parallel with and relative to said stationary means, said movable means presenting two longitudinally spaced lineally aligned rows of like equidistantly spaced numerals, and a pointer carried by said movable means between the latter rows of numerals and disposed for selective register with said first mentioned numerals; one of said rows of numerals on said movable means progressively increasing in value in one direction from said pointer and the other row of numerals on said movable means progressively increasing in value in the opposite direction from said pointer.

2. In a calculating device, a housing, stationary means in the housing presenting a longitudinal row of equidistantly spaced numerals progressively increasing in value from one end of said means to the other, movable means mounted in the housing for sliding movement parallel with and relative to said stationary means, said movable means presenting two longitudinally spaced

lineally aligned rows of like equidistantly spaced numerals, and a pointer carried by said movable means between the latter rows of numerals and disposed for selective register with said first mentioned numerals; one of said rows of numerals on said movable means progressively increasing in value in one direction from said pointer and the other row of numerals on said movable means progressively increasing in value in the opposite direction from said pointer, and means projecting from said housing for moving said movable means relative to said stationary means.

3. In a device of the class described, a box like housing having bottom, side and end walls, 15 said bottom wall having a medial longitudinal slot and presenting on its top surface, at one side of said slot, indicia denoting a series of longitudinally spaced numerals, a rectangular guide, means securing said guide in fixed position in said housing at the other side of said slot and spaced from the underlying portion of said bottom wall, a continuous flexible tape slidably mounted on said guide to move longitudinally thereof, said tape carrying indicia denoting a series of longitudinally spaced numerals arranged to register with said first named indicia in response to movement of said tape, a pointer secured to said tape and extending across said slot into position overlying said first named indicia, and a flexible operating member secured to said pointer and extending downwardly through said slot to be movable therealong.

4. The device of claim 3 wherein said pointer has opposed laterally opening recesses in its side edge portions; wherein said operating member is looped about said pointer and engages in said recesses; and wherein said operating member is disposed to engage a side wall of said slot.

5. The device of claim 3 wherein said pointer has bifurcations projecting from its free end in position to straddle said first mentioned numerals when moved into register therewith in response to movement of said tape.

6. The device of claim 3 wherein that portion 45 of the bottom wall which carries the first named indicia is relatively thick enough to display said indicia in substantially the plane of the top surface of said guide.

7. The device of claim 3 wherein said side walls 50 have opposed longitudinal grooves in their inner surfaces and wherein a transparent flexible sheet overlies said indicia and has its side edges yieldably engaged in said grooves.

8. In a calculating device, a stationary body 55 and a second body mounted for movement parallel and relative to the stationary body; one of said bodies carrying a longitudinal row of equidistantly spaced numerals progressively increasing in value from one end to the other, and said other body presenting two longitudinally spaced aligned rows of like equidistantly spaced numerals disposed for selective register with said first mentioned numerals, one of the latter rows of numerals progressively increasing in value in one direction and the other of said rows progressively increasing in value in the opposite direction; a pointer carried by the one of said bodies which carries said lineally aligned rows of numerals, said pointer being positioned between said lineally aligned rows of numerals, and means for moving said second body.

9. In a calculating device, a longitudinally slotted housing, stationary means in the housing presenting a longitudinal row of equidistantly spaced numerals progressing in value from one

end of said means to the other, movable means mounted in the housing for sliding movement parallel with and relative to said stationary means, said movable means presenting two longitudinally spaced lineally aligned rows of like equidistantly spaced numerals, and a pointer carried by said movable means between the latter rows of numerals and disposed for selective register with said first mentioned numerals; one of said rows of numerals on said movable means progressing in value in one direction from said pointer and the other row of numerals on said movable means progressing in value in the

opposite direction from said pointer, and means projecting from said housing for moving said movable means relative to said stationary means, said latter means comprising a flexible member attached to said movable means and projecting outwardly through said slot in said housing.
